226,503

PORTABLE REAR PROJECTION VIEWER

William A. Andres, Hopkins, Larry F. Becker, Brooklyn Park, and Larry D. Quanrud, Golden Valley, Minn., assignors to Washington Scientific Industries, Inc., Long Lake, Minn.

Filed Sept. 27, 1971, Ser. No. 184,312

Term of patent 14 years

Int. Cl. D16—03

U.S. Cl. D61—1 N

FIG. 1 is a front and right side perspective view of a portable rear projection viewer showing our new design; FIG. 2 is a left side elevational view thereof; FIG. 3 is a front elevational view thereof; FIG. 4 is a rear elevational view thereof; and FIG. 5 is a top plan view thereof.

We claim:

The ornamental design for a portable rear projection viewer, as shown.
